UNITED STATES PATENT OFFICE.

JAMES ALEXANDER FLANAGAN, OF TORONTO, ONTARIO, CANADA.

MOTOR-SUPPORT FOR SEWING-MACHINES.

1,335,163.

Specification of Letters Patent. Patented Mar. 30, 1920.

Application filed June 17, 1919. Serial No. 304,793.

To all whom it may concern:

Be it known that I, JAMES ALEXANDER FLANAGAN, a British subject, and resident of the city of Toronto, in the county of York and Province of Ontario, Dominion of Canada, have invented certain new and useful Improvements in Motor-Supports for Sewing-Machines; and I hereby declare that the following is a full, clear, and exact description of the same.

This invention relates to a motor support for sewing machines which will maintain the correct relation of the driving element of the motor with the flywheel of the machine, as hereinafter set forth and particularly pointed out in the claims, reference being had to the accompanying drawings in which:

Fig. 1, is a rear elevation of the motor support showing it attached to the arm of a sewing machine,

Fig. 2, is a side elevation of the same, with the flywheel removed,

Fig. 3, is a top plan view of the motor support detached from the sewing machine, on a larger scale than Figs. 1 and 2, and

Fig. 4, is a vertical section on the line *a—a*, Fig. 3.

For the attachment of the motor support to the sewing machine the vertical part *b* of the sewing machine arm *b'* has a slideway *a''* preferably of a dovetail formation, and the motor support has a slide *a* formed with a dovetail tongue *a'* to enter the slideway *a''* and provide for the vertical adjustment of the support relatively to the flywheel *k* of the sewing machine.

Operating transversely through the slide *a* is a set screw *c* adapted to bear against the inner surface of the slideway *a''* and press the dovetail tongue against the dovetail groove, to lock the slide in its vertically adjusted position.

Extending laterally-rearwardly from the slide *a* are the horizontal arms *i'* of a pair of upwardly curved standards *i*, and rigidly supported by the standards *i* is the motor supporting member *d* which is preferably of a cylindrical shape, and has a cylindrical bore *d'*, the diameter of which at its lower end is reduced to form an annular flange *d''*.

Contained within the bore *d'* is a helical spring *e*, the bottom coil of which is bent to form a downwardly extending arm *e'*, which enters within a corresponding aperture in the flange *d''* and holds the spring against rotation. The uppermost coil of the spring

is bent to form an arm *e* at right angles to the axis of the spring. This arm extends across the top surface of the supporting member *d* and is bent upwardly to form a crank *e'*. The purpose of the spring *e* is to yieldingly hold the pulley of the motor in contact with the flywheel *k*.

A plate *f* is mounted on the top of the supporting member *d* and is provided with a central screw threaded bore *f'* and two apertures *f''* in diametrical alinement through the center of the bore *f'*, for the screws by which the plate *f* is secured to the bottom of the motor and in the plate *f* is a radial slot *g'* to receive the cranked extremity *e'* of the helical spring *e*.

A pivot bolt *h* passes axially through the supporting member *d* and the spring *e*. The upper end of the bolt *h* is screw threaded to enter the screw threaded bore *f'* and engage with the screw threads therein and the lower end is formed with a head *h'* to engage the bottom of the supporting member and oscillatingly and removably connect the plate *f* thereto, the plate and the pivot bolt *h* serving as a coupling means for securing the motor to the support.

The motor may be of any ordinary type to drive the sewing machine and by this construction a simple and convenient means is provided for adjustably attaching it to the sewing machine arm, the slide permitting of the vertical adjustment of the support to bring the motor into correct driving relation with the sewing machine and the spring *e* applying a tension to the plate to maintain it in that position.

Having thus fully described my invention, what I claim as new and desire to secure by Letters Patent is:

1. A motor support for a sewing machine, comprising a supporting member, means oscillatingly mounted on said member for attachment to the motor, means yieldingly maintaining the fixed relation of the oscillating means to the supporting member, and means for attaching the supporting member to a sewing machine, said attaching means comprising a slide element for the vertical adjustment of the motor support.

2. A motor support for a sewing machine, comprising a cylindrical supporting member, a plate oscillatingly mounted on said member for attachment to the motor, means yieldingly maintaining the fixed relation of said plate to the supporting member and

- means for attaching the supporting member to a sewing machine, said attaching means comprising a slide element for the vertical adjustment of the motor support. 25
5. A motor support for a sewing machine, comprising a hollow supporting member, a plate oscillatingly mounted on said member, a coiled spring within the hollow supporting member, yieldingly maintaining the fixed relation of said plate to the supporting member, and a slide element for the vertical adjustment of the motor support. 30
10. 4. A motor support for a sewing machine, comprising a hollow supporting member, a plate oscillatingly mounted on said member, a coiled spring within the hollow supporting member, yieldingly maintaining the fixed relation of said plate to the supporting member, and means for attaching the supporting member to a sewing machine. 35
15. 5. A motor support for a sewing machine, comprising a supporting member, means for attaching it to the sewing machine, means oscillatingly mounted on said member for securing the motor thereto and means yieldingly maintaining the fixed relation of the oscillating means to the supporting member, said attaching means comprising a slide element for the vertical adjustment of the motor support. 30
20. 6. A motor support for a sewing machine, comprising a supporting member, a spring tensioned plate removably and oscillatingly mounted on said member and means for attaching the supporting member to the sewing machine, said means including a slide element for the vertical adjustment of the motor support. 35

Toronto, Canada, June 9th, 1919.

JAMES ALEXANDER FLANAGAN.
